UNITED STATES PATENT OFFICE.

LUCIEN EILERTSEN, OF PARIS, FRANCE.

DENTAL APPARATUS.

SPECIFICATION forming part of Letters Patent No. 709,973, dated September 30, 1902.

Application filed February 25, 1901. Serial No. 48,681. (No model.)

To all whom it may concern:

Be it known that I, LUCIEN EILERTSEN, a citizen of the French Republic, and a resident of Paris, France, have invented certain new and useful Improvements in Dental Apparatus, of which the following is a specification.

This invention has relation to dental apparatus, and it relates particularly to means for retaining sets of false teeth in the mouth.

In some instances the springs heretofore employed for retaining sets of false teeth in the mouth are objectionable both in mechanical and hygienic respects.

15 The object of the present invention is to prevent food from entering the interior of the springs by introducing soft india-rubber into the springs, and the surface thereof between the windings of the spring is made antiseptic 20 by immersing the spring thus filled with india-rubber in a solution of india-rubber containing antiseptic substances, or the spring is filled with antiseptic rubber.

In the accompanying drawings I have shown 25 the means enabling the springs to be removed as desired.

Figure 1 is a side view of a set of false teeth, showing a spring constructed and arranged in accordance with my invention. Figs. 2 30 and 3 are two views of the spring. Fig. 4 is a view of a plate, partly in section, showing the securing-hook for the spring. Fig. 5 is a view of a plate, showing the same provided with the securing-hook only. Fig. 6 shows

35 the spring applicable to the fastening device shown in Fig. 5, and Fig. 7 shows a plate provided with the rod 7.

In the drawings, 11 represent the ends of the spring 20, which ends are secured to plates 40 or buttons 2, to the centers of which are soldered rods 3, extending at right angles thereto. Each rod 3 extends freely into a tube secured to the plate of the teeth as a substitute for the ordinary nails. In order to prevent the rod from being disengaged from the tube, I employ a small hook 6, Fig. 4, resting on the plate to which the rod 3 is soldered. Said plate is provided with a notch 5, Fig. 2, so that in order to introduce the rod into the 45 corresponding tube said notch must be brought in front of the small hook projecting from the tube. Therefore there is but one

position in which the rod can enter the tube, and said position is determined so that the notch can never come in front of the hook 55 whatever position the spring may occupy in the mouth. Therefore the spring cannot be detached in operation. I may dispense with the tube and employ simply a pivot 7, terminating in a hook 6, as seen in Fig. 5. 60

As already described, a small plate 2 is secured to the ends 1 of the springs; but in the modified form said plate is provided with a hole 8 and a notch 5. There is but one position in which the spring may be detached 65 and attached. To this end the hole 8 must be fitted over the small hook 6. When the hole 8 has been engaged by hook 6, as just described, the plate 2 is but slightly turned. It will be impossible for the same to be disengaged unless the notch 5 is brought in front of the small hook 6. Therefore this modified construction involves the same principle as the construction first described, except that the tube is omitted and replaced by a pivot 70 75 7, Fig. 5, terminating in a hook to maintain the center of the plate 2. In either case the arrangement can only be disengaged in one position when the notch is in front of the small hook. The end of the small hook may 80 be free or connected to a rod 9, parallel to the rod 7, Fig. 7, thus forming a bridge, under which turns the plate 2 for the purpose of maintaining the hook 6. Said hook may be made of any suitable form, provided that the 85 principle of the system is not changed.

In order to prevent food from entering the interior of the spring, soft india-rubber is introduced into the same, and the surface between the windings of the spring is made 90 antiseptic by immersing the spring thus filled with india-rubber in a solution of india-rubber containing antiseptic substances, or the spring is filled with antiseptic rubber.

Having described my invention, what I 95 claim, and desire to secure by Letters Patent, is—

1. The combination with the two denture-plates and securing-hooks secured thereto, of a coiled spring, and small disks secured to 100 the ends of the spring and provided with notches in which the securing-hooks are adapted to engage.

2. The combination with the two denture-

plates and tubes secured therein and securing-hooks carried by said plates, of a coiled spring, small disks secured to the ends thereof and provided each with a notch within 5 which the securing-hooks engage, and pins secured to the disks and entering the tubes in the plates.

3. A coiled spring for use as described, provided with securing-disks at its ends, and

antiseptic soft rubber between the windings 10 of the spring.

In testimony whereof I have hereunto set my hand in presence of two witnesses.

LUCIEN EILERTSEN.
